(57) **CLAIM**

The ornamental design for a patterned cover for a lighting fixture, as shown and described.

DESCRIPTION

FIG. 1 is a perspective view of a patterned cover for a lighting fixture showing my new design;

FIG. 2 is a front elevational view thereof, the rear elevational view being identical thereto;

FIG. 3 is a right side elevational view thereof, the left side elevational view being identical thereto; and,

FIG. 4 is a bottom view thereof, the top view being hidden in use and forming no part of the design.

1 Claim, 4 Drawing Sheets
